(57) **CLAIM**

The ornamental design for a hot oven rack push/pull tool, as shown and described.

DESCRIPTION

FIG. 1 is an upper and bottom face view of a hot oven rack push/pull tool showing my new design.

FIG. 2 is a side view of the hot oven rack push/pull tool.

FIG. 3 is an end view of the lower push/pull end as shown in FIGS. 1 and 2; and,

FIG. 4 is an end view of the upper hanger orifice end as shown in FIGS. 1 and 2.
